UNITED STATES PATENT OFFICE.

ROBERT M. GILSON, OF PITTSBURGH, PENNSYLVANIA, ASSIGNEE TO THE UNION SWITCH & SIGNAL COMPANY, OF SWISSVALE, PENNSYLVANIA, A CORPORATION OF PENNSYLVANIA.

ELECTRICAL RELAY.

Application filed November 29, 1922. Serial No. 303,943.

My invention relates to electrical relays.

I will describe one form of relay embodying my invention, and will then point out the novel features thereof in the claim.

5 In the accompanying drawings, Fig. 1 is a view showing in end elevation one form of relay embodying my invention. Fig. 2 is a top view, partially sectioned, showing the relay shown in Fig. 1. Fig. 3 is a side view, partially sectioned, of the relay shown in Fig. 1. Fig. 4 is a fragmental view showing a modified construction of the contact bracket operating connections. Fig. 5 is a detail view showing the segment gear and 15 segment crank construction for the relay shown in Fig. 1. Fig. 6 is a detail view showing the contact mechanism of the relay shown in Fig. 1. Fig. 7 is an exploded view showing a stationary contact member and 20 means for fastening it to the top plate of the relay shown in Fig. 1.

Similar reference characters refer to similar parts in each of the several views.

Referring first to Figs. 1, 2, and 3, the 25 relay comprises a frame B of suitable material, such as cast iron, which frame is made up of a base plate 1 and four upstanding side members 12. These side members support a top plate A of suitable insulating material, such as porcelain. Each side member is provided with a glass wall C, which is held in place by a suitable rectangular casting attached to the side member by screws 12^A. In order to insure a tight fit the side 30 members 12 are ground to a true plane, and the four screws at the corners of the castings hold them tight against the frame member.

The frame B supports the operating mechanism of the relay, while the top plate A supports the contacts which are controlled by such mechanism.

The operating mechanism of the relay includes a C-shaped laminated iron yoke or 45 core 3, supported on bosses 2 which are integral with the base plate 1 and with core fastened to said bosses by means of machine screws 2^B. The core is provided with an energizing winding 29 in two sections located 50 on opposite sides, respectively, of the air gap in the core. These two winding sections are connected in series, and the leads 44 from the winding are in turn connected to two binding posts on the top plate of the relay, the

said leads being held in place along the side 55 of the relay by means of metal clips 43, riveted to the side of the frame and bent over the leads to hold them in place. Each pole of the core 3 is provided with a ferrule 28 of copper or other electro-conducting material 60 partially enclosing the pole face to produce a shifting magnetic field when the winding is supplied with alternating current.

The core 3 controls a vane or disk 17 of electro-conducting, non-magnetic material 65 such as aluminum, which vane is fixed to a shaft 27 provided with pivots which are preferably of non-corroding material. These pivots are mounted in non-corroding bearing screws 4^A which in turn are supported in 70 posts 4 integral with the bottom plate 1. The means for attaching the vane 17 to the shaft 27 comprises an aluminum casting 18 and a brass ring or washer 19 between which the said vane is riveted. The hub 18^A of the 75 casting 18 extends through the ring 19 and through the vane, and is in turn fixed to the shaft 27.

A pin gear 20, located on the shaft 27, is 80 connected thereto by means of a clutch mechanism which I will describe hereinafter, and this gear meshes with a segment gear 9. This segment gear is supported on, and fastened to, a counter shaft 7 having pivots, 85 preferably of some non-corroding material, supported in bearing screws 5^A, which in turn are supported in posts 5 integral with the bottom of the frame. The four bearing screws 4^A, 4^B, 5^A, 5^B, are all provided with lock nuts 4^B and 5^B, to maintain them in permanent adjustment. 90

A crank 8 is also fixed to the counter shaft 7 and to the segmental gear 9 at the shoulder 8^A. (See Fig. 5). This crank is of aluminum or other suitable material having a stud 8^C 95 into which is screwed a weight rod 10, and the crank is also provided with two lips 8^D between which a link 30, Fig. 1, is pivotally connected.

This link 30 has an insulated joint 30^A, 100 comprising two strips 30^B of micarta or similar insulating material, and four strips 30^C of aluminum, riveted together, substantially as shown, to splice the break in the member 30. This link transmits the motion of the crank 8 to an arm 31 in one form of my invention. This arm 31 controls a plurality of contacts which I will now describe. 105

Referring to Figs. 1, 3 and 6, a contact spring bracket 33, of strip steel or other suitable material, has upstanding ends which are provided with pivot pins 35 mounted to swing in bearing screws 32^a. This bracket 33 is operated by means of the arm 31 pivotally connected to the insulated link 30. A U-shaped yoke 34, Figs. 2, 3 and 6, is riveted to the center of the lower side of this bracket 10 and the portion of the bracket within its legs is cut out to provide clearance for the vane 17.

The contact bracket 33 is provided with a plurality of flexible contact members 37 (see Fig. 6) each comprising a back spring 37^b attached to the bracket 33 by means of insulating studs 36. A flexible contact finger 37^c is riveted to each end of the back spring, said contact fingers having silver tips 37^a riveted thereto which engage with the fixed contact member that will be hereinafter described.

Each of these movable contacts 37 is connected to a binding post 41 immediately above, said connection being made by means of a flexible copper conductor 38 attached to the screw head 39 on the under side of the top plate A.

The fixed contact post D or C with which the flexible contactors coat are provided (see Fig. 7) with tips of graphite 40^b, fastened to the spacer 40^a, which in turn is connected to the binding post 41. The graphite contact tip 40^b is clamped to a ferrule 40^c which is in turn clamped to the spacer 40^a. The screw 41^c of the binding post 41 has a square head 41^a, too large to turn in this spacer, and a nut 41^b, to draw said spacer up tight against the seat 41^d, which bears on the top plate A. This nut fits into the recess 45 which is then filled with sealing wax or some other suitable material, the purpose being to prevent tampering with the binding post from outside the relay. A lock nut 41^e and a washer 41^f clamp down on the top and offer support for the standard washers and nuts of the binding post.

The segment gear 9 is a 90° segment, provided, as shown in Fig. 3, with metal clips 50 9^a riveted to its edge and abutting against stops 15 and 16 which limit the motion of the gear. The shock caused by the sudden arresting of the motion of this gear is absorbed by the clutch mechanism hereinbefore mentioned and which I will now describe.

A brass disk 21 is riveted to the shaft 27. Another and smaller disk 26, having a hole in its edge for the end of a coil spring 25, is also riveted to the shaft. The pin gear, which is of the squirrel cage type, comprises a hub of metal, preferably brass, and two flanges 23 integral therewith which carry around their peripheries a plurality of steel pins 20^a equally spaced. These pins or teeth

are preferably polished stainless or non-corrodible steel rods about $1/6$ " in diameter and are free to rotate in the supporting cage, thus taking up some of the sliding friction between the gear segment teeth and the pinion and allowing new surfaces to come into contact. The gear is interposed between two fiber friction washers 22, and the combination of said gear and said washers is supported upon the shaft 27, free to rotate, but held in close contact with the fixed disk 21 by the pressure of the spring 25 against another disk 24 having two pins 26^a between which the end of the said spring is held fast. Thus the shock of the impact of the gear 9 against the stop 15 or the stop 16 is absorbed either in friction on the fiber disks, or by torsion of the spring, or by both, and so the pivots and other small parts are protected from undue stain. The material and dimensions of the said spring are such as to give positive motion of the pinion under steady torque exerted by the shaft, or vice versa, within the limits of the motion of the segment gear. When the relay is energized the shaft 27 tends to rotate in a clockwise direction, as shown in Fig. 3. Reference to Fig. 2 will show that this motion tends to uncoil the spring 25, thereby increasing the pressure on the friction disks 22 and thus insuring positive rotation of the pinion. On the other hand, when the relay is de-energized and the segment gear strikes the stop as hereinafter explained, the inertia of the vane and other moving parts tends to wind up the coil spring, thus reducing the pressure on the friction disks and hence allowing the clutch mechanism to slip more readily.

It will be noted that as shown in Fig. 1 the spring contact support 33 is grounded to the frame B of the relay, by a flexible copper conductor 33^a to avoid freezing of the relay in the energized position due to heavy discharge of lightning through the pivots and bearing screws.

In the form of my invention described herein I have incorporated breather holes 14 in the bottom plate 1 (see Fig. 2), fitted with small mesh metal gauze. These breather holes allow free circulation of air but prevent the entrance of insects, dirt or other foreign matter.

In the accompanying drawings all parts are shown in the positions corresponding to the de-energized condition of the motor device of the relay. When alternating current of the proper value passes through the windings 29, the vane 17 is caused by induction motor action to rotate in clockwise direction, as viewed in Fig. 3, causing the pinion 20 to drive the segment gear 9 in counter clockwise direction. This motion, communicated to the contact bracket, opens the back contact C and closes the front contacts D. The remainder of the motion, until

the segment gear clip 9^a strikes the stop 16, causes the front contact tip to slide upon the fixed contact member 40.

As long as the windings of the motor device are energized the contacts are held in this position against the torque exerted by the counter weights 11. When the motor device is de-energized, these weights act to return the segment gear into its original position. About midway of its motion the front contact D opens, and soon after the back contact C closes. The segment gear continues to move downward, under the propulsion of the weights 11, till the clip 9^a strikes the stop 15. Because of the inertia of the moving parts and the comparatively large distance the segment must move before the contacts reverse, a considerable interval of time elapses after de-energization before the contact operation occurs. The duration of this time may be regulated by the size of the weights 11, and by their distance from the center of the shaft which may be varied by screwing them up or down on the rod 10.

A modification in the method of communicating the motion of the motor device to the contact bracket is shown in Fig. 4. In place of the rigid arm 31, I provide a flexible spring member 48 affixed to the top of the bracket 33, and having an eye 49 formed in its end whereby it is pivotally attached to the insulated link 30. A stiff member or back spring 47 is attached to the under side 7 of the bracket 33, and in the position corresponding to the de-energized condition of the motor device, rests against the spring member 48. An outstanding lug 51, is provided on the relay frame, and a screw 52 is adjustably mounted in this lug and is held in permanent adjustment by a lock nut 50.

The operation of this combination is as follows: When the motor device is energized its motion as previously described serves to move the link 30, upward. This motion is communicated by the spring 48 to the bracket 33 which moves about its pivots till the back contacts open and the front contacts close, whereupon the yoke 34 engages the screw 52, which prevents further movement. The spring 48 absorbs any further movement of the link 30 in flexure, thus relieving the contact finger 37 of excessive pressure. The stiff back spring 47 is provided to prevent flexure of member 48 when in de-energized position by engaging said member near the eye 49 and thus insuring good pressure at the back contact D.

Although I have herein shown and described only one form of relay embodying my invention and one modification thereof, it is understood that various changes and modifications may be made therein within the scope of the appended claims without departing from the spirit and scope of my invention.

Having thus described my invention, what I claim is:

A relay comprising a metal frame, a top plate of insulating material, a metal contact-operating bar pivotally supported from said top plate, a motor and reduction gearing supported by said frame, a connection between said gearing and said bar including a link made up of two parts electrically insulated from each other, and an electrical connection from said bar to said metal frame.

In testimony whereof I affix my signature.

ROBERT M. GILSON.
